US0D1066330S

(12) **United States Design Patent** (10) Patent No.: **US D1,066,330 S**
(45) Date of Patent: ** Mar. 11, 2025

(54) **ELECTRONIC DEVICE**

- (71) Applicant: **Dwellwell Analytics, Inc.**, Bethesda, MD (US)
- (72) Inventors: **Edwin Laurence Booth**, Brooklyn, NY (US); **Nina Gabrielle Simpkins**, Bethesda, MD (US); **Daniel Simpkins**, Bethesda, MD (US); **Mikael Plougstrup Nielsen**, Copenhagen (DK)
- (73) Assignee: **Dwellwell Analytics, Inc.**, Bethesda, MD (US)
- (**) Term: **15 Years**
- (21) Appl. No.: **29/825,343**
- (22) Filed: **Jan. 31, 2022**
- (51) LOC (15) Cl. **14-02**
- (52) U.S. Cl. **D14/356**
- (58) **Field of Classification Search**
USPC D10/70, 104.1, 106.1–106.6, 118; D8/330, 332, 343, 346; D14/358
CPC G08B 13/02; G08B 13/08; G08B 13/1463; G08B 13/2491

(57) **CLAIM**

The ornamental design for an electronic device, as shown and described.

DESCRIPTION

FIG. 1 is a front perspective view of an electronic device showing the claimed design.

FIG. 2 is a rear perspective view of the electronic device.

FIG. 3 is a front view of the electronic device.

FIG. 4 is a rear view of the electronic device.

FIG. 5 is a left side view of the electronic device.

FIG. 6 is a right side view of the electronic device.

FIG. 7 is a bottom view of the electronic device; and,

FIG. 8 is a top view of the electronic device.

The broken lines in the drawings illustrate portions of the electronic device that form no part of the claimed design.

1 Claim, 7 Drawing Sheets
